UNITED STATES PATENT OFFICE

94,923

DESIGN FOR A FIRE KINDLER BRIQUETTE

Charles Skeele Palmer, Pittsburgh, Pa., assignor of two-thirds to Jacob Gold, Pittsburgh, Pa.

Application May 20, 1932, Serial No. 43,855

Term of patent 14 years

To all whom it may concern:

Be it known that I, Charles Skeele Palmer, a citizen of the United States, residing at Pittsburgh, in the county of Allegheny and State of Pennsylvania, have invented a new, original, and ornamental Design for a Fire Kindler Briquette, of which the following is a specification, reference being had to the accompanying drawing, forming part thereof.

The figure is a perspective view of a fire kindler briquette, showing my new design.

I claim:

The ornamental design for a fire kindler briquette, as shown.

CHARLES SKEELE PALMER.
